Patented Aug. 1, 1922.

UNITED STATES PATENT OFFICE.

ENRIQUE JUAN BENOIST, OF VIÑA DEL MAR, CHILE.

GRADE SIGHT.

1,424,613.

Specification of Letters Patent. Patented Aug. 1, 1922.

Application filed January 21, 1920. Serial No. 353,015.

To all whom it may concern:

Be it known that I, ENRIQUE JUAN BENOIST, a citizen of the Republic of Chile, South America, have invented new and useful Improvements in Grade Sights, of which the following is a specification.

My invention relates to improvements in grade-sights, adapted for use in ascertaining the grade or slope in underground work, 10 while not necessarily restricted to this use.

An important object of the invention is to provide a device of the above mentioned character, which is simple in construction, convenient in use, and embodying elements 15 which may be separated so that the device may be carried in the pocket or the like.

Other objects and advantages of the invention will be apparent during the course of the following description.

20 In the accompanying drawings forming a part of this specification, and in which like numerals are employed to designate like parts throughout the same,

Figure 1 is a side elevation of a device 25 embodying my invention,

Figure 2 is a plan view of the same,

Figure 3 is a transverse section taken on line 3—3 of Figure 1, looking in the direction of the arrows. Figure 4 is a longitudinal section taken on line 4—4 of Figure 30 2, and,

Figure 5 is a side elevation of a V-sight.

Figure 6 is a fragmentary view with parts 35 broken away showing the manner of calibrating the instrument, and Figure 7 is a fragmentary perspective view, illustrating the forward end of the device and showing the complete end sight.

In the drawings, wherein for the purpose 40 of illustration is shown a preferred embodiment of my invention, the numeral 10 designates the body portion of the device, which is trough-shaped, or U-shaped in cross section. The top of the body portion 10 is open, 45 and its sides 11 are provided at points equidistantly spaced with openings or notches 12. Arranged at these openings or notches, are plates 13, secured to the outer surfaces of the sides 11 by screws 14 or the like. The 50 plates 13 are provided with openings 15, forming hooks 16, the notches 17 of which are equi-distantly spaced from the ends of the body portion 10. The hooks 16 are adapted to engage with a line or cord 18, 55 which is preferably strong and fine.

The numeral 18 designates a plate, se-

cured to the bottom of the body portion 10, at its center, by screws 19. This plate has an internally screw-threaded socket 20, depending therefrom for detachably receiving 60 a screw-threaded stud 21, carried by a plumb-bob 22, which is preferably formed of metal, to impart to the same a suitable weight. This plumb-bob, when the body portion 10 is suspended from the cord 18, will hold 65 the same in a horizontal position. The plumb-bob 22 may be separated from the body portion, when desired, for convenient handling of the device or placing the same in the pockets or the like.

70 Arranged within the forward end of the body portion 10 is a scale plate 23, held stationary by screws 24 or the like. This scale plate has an upstanding flange 25, provided with a sight-opening 26. The numeral 27 75 designates an end sight element, having its inner end attached to the body portion 10 by screws 28 or the like. The end sight 27 has an upstanding blade or knife edge 29, arranged inwardly of and contacting with 80 the flange 25. The forward end of the end sight 27 may be raised and lowered with respect to the flange 25, by means of an adjusting screw 30, engaging within a sleeve or bushing 31 and passing through an opening 32 in the scale plate 23.

75 In the rear end of the body portion 10 is arranged a reflector 33, disposed at an angle of 45° to the horizontal, and fitting within slots 34. This reflector is held in place by a 90 top plate 35, engaged by a screw 36. The reflector 33 is provided upon its upper surface with a horizontal line 37. This reflector may be formed of a looking-glass or any other suitable material.

95 The end of the body portion near the reflector is also provided with vertical grooves 38, which are adapted to receive the edges of a rear V-sight 39, when the reflector is not used.

100 The forward end of the body portion of the device 10, is provided with a scale plate 40, as shown by Figure 6, with a unit of measurement as shown. In use and for the purpose of calibration of the grade-sight, the 105 member 23 may be removed, leaving the knife edge front sight in its same relative position. This knife edged sight has indicated upon its surface adjacent to the said unit of measurement on the scale plate, a 110 fixed mark 41 normally coinciding with the zero mark of the plate. In computing the

degree of elevation or declination of an object, in the distance, the adjusting of the knife edged sight by means of the adjusting screw will show the degree of such elevation or declination thus forming a basis for the calibration.

In the use of the device, a string is stretched more or less horizontally at a convenient height, and more or less perpendicular to the drift. This string is located near a point from which an elevation can be readily taken, thus for instance from a rail, which has been set at a selected grade. The body portion 10 of the device will now assume a horizontal position, and the height of the line of sight of the device is taken from the known level, in this instance the rail. This height is then marked upon a stick or the like previously employed to ascertain the above referred to height, and such stick is carried forwardly to the place where the grade is required, and placed vertically. The point upon the stick may be easily found by running up or down the stick with an acetylene light, and when this correct point of the light coincides with the line of sight of the device, the point of light will be at the line 37. The operator then marks on the stick, the point of the light, which may be above or below the previous mark upon the stick, and the distance between these two points may be considered as a plus or minus quantity, corresponding to the grade sought.

The reflector 33 may be removed and the V-sight 39 employed, the operator then standing behind the instrument and looking through the V-sight, to ascertain a point upon the stick which is in the line of sight of the instrument.

It is to be understood that the form of my invention herewith shown and described is to be taken as a preferred example of the same, and that various changes in the shape, size, and arrangement of parts may be resorted to without departing from the spirit of my invention, or the scope of the subjoined claims.

Having thus described my invention, I claim:

1. A grade sight of the character described, comprising a trough-shaped body portion, plates secured to the sides of the trough-shaped body portion and carrying hooks, a plumb-bob detachably connected with the bottom of the body portion and depending therefrom, a scale held within the forward end of the body portion, an end sight held within such forward end in proximity to the scale, means to vertically adjust the

end sight with relation to the scale, and an 60 angularly arranged reflector held within the rear end of the body portion.

2. A grade sight of the character described, comprising a trough-shaped body portion, plates secured to the sides of the 65 body portion and carrying suspension elements, a plumb-bob detachably secured to the body portion between the ends thereof, a scale held within the forward end of the body portion, an end sight held within such 70 forward end and engaging the scale, means to vertically adjust the end sight with relation to the scale, and a coacting sighting device secured within the rear end of the body portion.

3. A grade sight of the character described comprising a trough shaped body portion, plates secured to the sides of the body portion and carrying suspension elements, a plumb-bob detachably secured to the 80 body portion between the ends thereof, a scale placed within the forward end of the body portion comprising a plate with a unit of measurement thereon, an end sight adjacent to said plate having a horizontal indicating mark normally registering zero with relation to the scale plate, means to vertically adjust the end sight with relation to the plate, and a coacting sight-device secured within the rear end of the body portion.

4. A grade sight of the character described, comprising a body portion provided between its ends with suspension means, a plumb-bob secured to the body portion between its ends, a sighting device arranged upon the forward end of the body portion and a reflector arranged upon the rear end of the body portion having a line thereon adapted to coact with the sighting device. 100

5. A grade sight of the character described, comprising a body portion provided between its ends with suspension means, a plumb-bob secured to the body portion between its ends, a sighting device arranged upon the forward end of the body portion consisting of a scale plate having an upstanding flange provided with a sight opening and scale markings along one side of said opening, an end sight element having 110 an upstanding blade or knife edge and a fixed mark cooperable with the scale markings of said scale plate, and means for vertically adjusting said knife edge, and a coacting sight device arranged upon the rear 115 end of said body portion.

ENRIQUE JUAN BENOIST.
